UNITED STATES PATENT OFFICE.

GEORGE S. TURNER, OF EDGEWOOD, PENNSYLVANIA, ASSIGNOR TO WESTINGHOUSE ELECTRIC & MANUFACTURING COMPANY, A CORPORATION OF PENNSYLVANIA.

FLUID-PRESSURE ACTUATING DEVICE.

Application filed July 14, 1923. Serial No. 651,594.

My invention relates to fluid pressure actuating mechanism, more especially to control means for fluid pressure systems for actuating the hydraulic rams of punch presses, bull dozers, coil and pressure molding machines and the like.

It is among the objects of my invention to provide a control mechanism for fluid pressure actuated devices which shall be manually operative and which shall provide substantially absolute safety for the operator without impairing the efficiency and speed of the control mechanism.

It is another object of this invention to provide a device of the above designated character which shall be of simple, compact and durable construction, which shall be relatively inexpensive and adapted to be readily applied to standard machines which are operated by fluid pressure systems such as steam, water, gas, air and the like.

Liquid pressure actuated machinery is usually of the type wherein the working members constitute a plurality of co-operating parts movable relatively to each other, such as the steam platens of hydraulic presses, the forms of coil molding machines and the dies of bull-dozers and drop forging apparatus. All of these are very dangerous to the operator who is apt to work on the movable parts, such as inserting or removing materials and simultaneously operate the control mechanism.

My present invention is directed to a control mechanism which requires that the operator employ both hands in its manipulation to actuate the machinery.

My device is further provided with a liquid-actuated automatically-operating safety link which automatically cuts out the supply source when the pressure therein is reduced to a calibrated minimum value.

In the accompanying drawings constituting a part hereof and in which like reference characters designate like parts,

Figure 1 is a view partially in plan and partially in section of a mechanism embodying my invention.

Fig. 2 is a side elevational view thereof, Fig. 3 is a view partially in plan and partially in cross-section along the line III—III of Fig. 2, of one of the valve members illustrated in Figs. 1 and 2,

Fig. 4 is a view taken along the line IV—IV of Fig. 2, of a guide bracket embodied in the valve mechanism of Fig. 3, and

Fig. 5 is a view of a guide bracket and serrated cam member taken along the line V—V, Fig. 2.

Referring to Figs. 1 and 2, the control mechanism comprises a fluid pressure feed line 1 connected to a feed pipe 2, of a press or the like, through a plurality of valves 3 and 4 connected by a feed line 5 and secured to a suitable base 6. The valve members 3 and 4 are of the three-way type having three ports constituting respectively, inlet, feed and exhaust openings which in the illustrations are connected respectively to the feed line 1 of the valve 3, and the feed line 5 of the valve 4 on their intake ports, the line 5 on the valve 3 and the feed line 2 of the valve 4 for the feed pressure ports and the elbows 7 and 8 respectively for the exhaust ports.

The valve member 3 (Fig. 3) is provided with a stem 10 that has a notched collar 12 secured thereto by a dowel pin 13. A handle 14 is disposed around the collar 12 and is adapted to rest against a stop pin 15 provided in the offset portion 16 of the valve stem support. The handle 14 is hollow and is provided with a plunger 18 having a chamfered end portion 19 adapted to engage a correspondingly shaped notch in the collar 12 and its other ends is connected by a tension spring 20 to a plug 21 fixed in the end of the handle. The plunger 18 is provided with a transverse slot adapted to receive a thumb lever 22 pivotally supported by a pin 23 on the handle 14.

A guide bracket 25 is secured to the valve stem 10 underneath the base 6. This bracket is of segmental form and is provided with an angular notch 26 which is adapted to rest against a stop pin (not shown). The outer periphery 27 of the bracket 25 is provided with a groove 28 for receiving a cord or wire 29 which is fastened by a pin or screw 30 at one end and to a coil spring 31, Fig. 1, at its other end in such manner that the spring 31 biases the valve towards the closed position. The bracket 25 is further provided with a radial finger 32 which is pivotally secured to a link 33, Figs. 1 and 4.

The link is pivotally connected at the joint 34 to a rod 35 extending longitudinally of the base 6 to the valve member 4.

The valve member 4 is provided with a 5 valve stem 11 that has mounted thereon a cam member 37 having a serrated surface 38 that is disposed to engage the end of the rod 35. A handle 17 is secured to the valve stem 11 and is disposed to rest against a stop pin 10 49 when the valve is in the normal or inoperative position. Beneath the cam member 37 and journaled on the valve stem 11 is a 15 guide bracket 36 having an annular segmental slot 40 that is disposed to cooperate with 20 a stop pin 39 on the cam member 37. The 25 guide bracket 36 is also provided with a projecting finger 41 that is pivotally connected to a link 43 by a pin or bolt 42. The link 43 is pivoted to a plunger 44 that is movably mounted in a bracket 45 underneath the base and that projects into a cylinder 46 that is disposed adjacent the valve member 3. The plunger 44 is provided with a coil 30 spring 47 that rests against the bracket 45 at one end and against an adjustable nut 48 at its other end in such manner that it biases the plunger 44 towards the cylinder 46. To overcome the action of the spring 47 fluid pressure may be admitted to the 35 cylinder 46 by means of a port 50 that is connected to the feed line 5 of the valve 3 by a pipe 51.

In the inoperative position of the device the parts assume the positions indicated in 35 Fig. 1, that is, the handles 14 and 17 are on the left-hand side to close the intake ports of the pipes 1 and 5, and to connect the pipes 5 and 2 to the exhaust ports 7 and 8, the handles resting against the stop pins 15 40 and 49. In this position of the device, the rod 35 is engaged in the notch 52 of the serrated cam 37, thus preventing any movement of the valve stem 11. The plunger 44 is in the position shown in Fig. 1 with the 45 spring member 47 in extended position between the bracket 45 and nut 48.

To transmit pressure through the system to the feed line 2, the handle 14 is moved in the direction of the spring member 47 thus 50 permitting fluid to enter from the supply line 1 through the respective ports to the pipe line 5 and through the feed pipe 51 to the cylinder 46 causing the plunger 44 to be advanced against the compression of the 55 spring 47 thereby moving the guide bracket 36 away from the stop pin 39. By the manipulation of the handle 14 of the valve 3, the rod 35 is moved longitudinally of the base 6 out of the notch 52 of the cam 37, thus 60 permitting the handle 17 to be moved to thereby open the port leading to the feed line 2 a corresponding amount. The amount of pressure at the feed line 2 is dependent on the openings of the ports which vary 65 with the movement of the handles 14 and

17. It is necessary to manipulate the lever 14 simultaneously with the lever 17 to operate the rod 35 and to permit the cam 37 to be rotated and advanced step by step along the serrated surface 38.

When the valves 3 and 4 have been opened to the desired extent the handles 14 and 17 may be released and the valves will remain in the position determined by the engagement of the rod 35 with one of the steps of 70 the serrated surface 38 of the cam member 37. If the pressure in the supply line 1 becomes reduced below a predetermined amount the spring 47 will overcome the force exerted by the fluid upon the end of the 75 plunger 44 and will cause the bracket 36 of the valve 4 to be turned in such manner that the slot 40 will receive the stop pin 39 on the cam 37 and turn the cam and valve stem 11 to the inoperative position.

When the cam 37 is turned to the inoperative position the rod 35 will be released and the spring 31 will close the valve 3. This 80 feature of the device is provided to guard against the possibility of the valves being left in the open position when the fluid pressure is shut off at some other point in the supply line thereby permitting the fluid actuated device to be inadvertently operated when the pressure is again turned on.

A further safe-guard against inadvertent operation is the spring-supported plunger 100 85 18 which requires that the operator's thumb be pressed against the latch 22 to effect contact with the valve stem collar 12, thus preventing any fixing of the handle as by a weight or string to hold it in its operative position.

It will be readily understood from the 105 above description of my invention that a control mechanism embodying the principles thereof provides a safe and efficient means for controlling the operation of fluid-pressure actuated machines.

Although I have described a specific embodiment of my invention, it will be obvious to those skilled in the art that various modifications may be made in the details of construction without departing from the principles herein set forth. For instance, the 110 general arrangement and design of the operating parts may be varied in accordance with the service requirements or operating conditions in which my device is utilized and still remain within the spirit and scope 115 of the invention as defined in the appended 120 claims.

I claim as my invention:—

1. A fluid pressure actuating device comprising a plurality of manually operated 125 mutually dependent valves and means associated therewith for automatically releasing the same in the event of failure of the fluid pressure.

2. A fluid pressure actuating device com-

prising a plurality of manually operated mutually dependent valves and means associated therewith for automatically rendering the device inoperative in the event of failure of the fluid pressure.

3. A fluid pressure actuating device comprising a plurality of manually operated mutually dependent valves and means comprising a fluid actuated spring-supported plunger connected at one end to one of said valves for closing the valves in the event of failure of the fluid pressure.

4. Fluid pressure control means comprising a pair of valves connected intermediate a supply line and a pressure feed line, a plurality of movable guide brackets associated with the stems of said valves, links connecting said brackets and means for changing the stop position of one of said brackets by the operation of the other.

5. Fluid pressure control means comprising a pair of valves connected intermediate a supply line and a pressure feed line, a plurality of guide brackets associated with the stems of said valves, a serrated cam associated with the stem of one of said valves, links connecting said brackets and cam, tension means associated with said brackets and links, and handles on said valve stems.

30 6. Fluid pressure control means comprising a pair of valves connected intermediate a supply line and a pressure feed line, a plurality of guide brackets associated with the stems of said valves, a serrated cam associated with the stem of one of said valves, links connecting said brackets and cam, tension means associated with said brackets and links, and handles on said valve stems, said handles being manually operative and adapted to be manipulated simultaneously.

45 7. Fluid pressure control means comprising a pair of three-way valves interconnected and connected respectively to a supply line and a pressure feed line, each having an exhaust port, means for effecting communication between the supply line and the feed line while simultaneously isolating the exhaust ports and automatic means for rupturing such communication.

50 8. Fluid pressure control means comprising a pair of three-way valves interconnected and connected respectively to a supply line and a pressure feed line, each having an exhaust port, means for effecting communication between the supply line and the feed line while simultaneously isolating the exhaust ports and automatic means for rupturing such communication, said means comprising a pair of manually operative handles associated with connecting links

and movable stop members, the latter being spring actuated and dependent upon the pressure in the system for their operation.

9. In a control mechanism for fluid pressure actuated devices the combination with a feed line, of two valves in series in the feed line, handles on the valves for operating them, resilient means for biasing the valves towards the closed position, fluid pressure actuated means controlled by the first valve for overcoming the resilient closing means for the second valve and mechanical means controlled by the position of the second valve for latching the first valve in the open position.

10. In a control mechanism for fluid pressure actuated devices, a valve member having an inlet and a feed port, a spring associated with said valve for closing it, a second valve member in series with the feed port, a spring element for closing the second valve, fluid pressure actuated means for counteracting the force of said spring element, said means being controlled by the first valve.

11. In a control mechanism for fluid pressure actuated devices, a plurality of valve members having inlet and feed ports, springs associated with said valve members for biasing them towards the closed position, fluid pressure actuated means associated with one of said valve members for counteracting the effect of the spring, said fluid pressure being controlled by another of said valve members.

12. The combination with a fluid pressure supply line of two valves in series for controlling the flow of fluid in the supply line, means for interlocking said valves to restrain the second valve from being opened before the first valve and resilient means for closing both valves, said means being actuated by a predetermined reduction of the fluid pressure in the supply line.

13. The combination with a fluid pressure supply line of two valves in series for controlling the flow of fluid in the supply line, means for interlocking said valves to restrain the second valve from being opened before the first valve and to restrain the first valve from being closed before the second valve, resilient means for biasing the valves towards the closed position, means for latching the valves in an open position and means respondent to a predetermined reduction of the fluid pressure in the supply line for releasing the latching means.

In testimony whereof, I have hereunto subscribed my name this 11th day of July 1923.

GEORGE S. TURNER.
